UNITED STATES PATENT OFFICE.

CHARLES DE QUILLFELDT, OF NEW YORK, N. Y., ASSIGNOR TO JACOB WEIDENMANN, OF SAME PLACE.

BUTTON-FASTENING.

SPECIFICATION forming part of Letters Patent No. 268,462, dated December 5, 1882.

Application filed January 18, 1882. (No model.)

To all whom it may concern:

Be it known that I, CHARLES DE QUILLFELDT, a citizen of the United States, and residing in the city, county and State of New York, have invented a new and useful Button-Fastening, of which the following is a specification.

My invention relates to improvements in self-fastening buttons and analogous articles, such as badges, &c.

I attain the objects of my invention (which are ease of adjustment and removal from the fabric and strength and utility of the fastening) by the device illustrated in the accompanying drawings, in which similar letters refer to similar parts throughout the several figures and views.

The button may be made of metal, bone, horn, celluloid, or other substance, and may be covered with a textile fabric or not, as desired.

A, Fig. 1, shows a sectional view of the complete button, and B, Fig. 1, shows a perspective view.

25 A, Fig. 2, shows an inside view of the bottom disk, in which are contained the springs hereinafter referred to.

B, Fig. 2, shows a washer, which is placed upon the bottom disk to keep the springs in place, but may be dispensed with in flat buttons, if desired.

C, Fig. 2, is the cap of the button.

A, Fig. 3, shows the spring carrying the bolt hereinafter referred to.

35 B, Fig. 3, shows the curved shank, which serves as the fastening, hinged to the button by the spring s.

C, Fig. 3, shows a perspective view of the bottom of the button.

40 My button is constructed in the following manner: In a circular disk having two concentric annular depressions I lay two circular springs—one in each depression. The outer of these springs, o, has one end bent at right angles, and this bent end serves as the bolt b. I hinge the curved shank t to the springs and pass it through a hole in the bottom disk of

the button, Fig. 1. The point of the curved shank t passes through another hole in the bottom disk, and has an eye near its point, 50 which the bolt b slides into and locks the shank. The fastening is on the principle of the ordinary spring-padlock. The cap of the button is then secured upon the bottom disk in the ordinary manner. To unlock the button, I 55 insert a pin or other pointed instrument through a hole, e, in the bottom of the button, and thereby push back the spring o, which carries the bolt b. The shank t is thus released and can be withdrawn from the fabric, to which 60 the button is secured. The button is attached by passing the shank through the fabric and inserting the point in the hole prepared for it until the bolt of the spring engages in the eye of the shank.

What I claim is—

1. A button provided with a hook-shank hinged within the bottom plate, adapted to hook into the material for attachment, the pointed end of the hook being detachably secured within the bottom plate, all substantially as set forth.

2. The combination, in a button-fastening, of a hinged shank which passes through the fabric to which the button is to be secured, 75 and a spring which secures the point of the shank to the button, substantially as shown and described.

3. The combination, in a button-fastening, of a hinged shank which passes through the 80 fabric to which the button is secured, and a spring carrying a bolt, which passes into an eye in the point of the shank and secures the fastening, substantially as shown and described.

4. The combination, in a button-fastening, of the hinged shank t, having an eye in it, the springs s and o, bolt b, and hole e, all combined with cap and bottom disk of the button, substantially as and for the purpose set forth.

CHARLES DE QUILLFELDT.
